DESIGN FOR A TRASH RECEPTACLE

Maurice Lumley, Cincinnati, Ohio, assignor to
The F. H. Lawson Company, Cincinnati, Ohio, a corporation of Ohio

Application August 8, 1940, Serial No. 94,313

Term of patent 14 years

To all whom it may concern:

Be it known that I, Maurice Lumley, a citizen of the United States and a resident of Cincinnati, in the county of Hamilton and State of Ohio, have invented a new, original, and ornamental Design for a Trash Receptacle, of which the following is a specification, reference being had to the accompany drawing, forming a part thereof.

In the drawing:

I claim:

The ornamental design for a trash receptacle, substantially as shown.

MAURICE LUMLEY.
